UNITED STATES PATENT OFFICE.

MIKE SLAWIENSKI, OF CAMDEN, NEW JERSEY.

HOUSEHOLD INDICATOR.

Application filed March 29, 1923. Serial No. 628,543.

To all whom it may concern:

Be it known that I, MIKE SLAWIENSKI, a citizen of Poland, residing at Camden, in the county of Camden and State of New Jersey, have invented new and useful Improvements in a Household Indicator, of which the following is a specification.

My invention relates to new and useful improvements in a household indicator, and 10 has for its primary object to provide means operable by a person calling at a dwelling and the occupants of such dwelling to indicate who the caller is and the wishes of the occupants.

15 Another object of my invention is to provide a number of dials having indications, thereon, one of which is located on the outside of the building or near a door, and each provided with a pointer adapted to be simultaneously actuated so that when one is moved to an indication all others will be moved to a similar indication.

With these ends in view, this invention consists in the details of construction and 25 combination of elements hereinafter set forth and then specifically designated by the claim.

In order that those skilled in the art to which this invention appertains, may understand how to make and use the same, I will 30 describe its construction in detail, referring by numerals to the accompanying drawings forming a part of this application in which:—

35 Fig. 1, is a front elevation of one of the units utilized in the embodiment of my invention.

Fig. 2, is a sectional side elevation thereof illustrating one method of installation.

40 Fig. 3, is a fragmentary sectional side elevation on the line 3—3 of Fig. 4, of a slightly modified form of unit.

Fig. 4, is a face view thereof.

Fig. 5, is a front elevation of a simple arrangement of my invention wherein the indications are to be made at only two points.

Fig. 6, is an edge view thereof.

Fig. 7, is a semi-diagrammatic view illustrating an arrangement by which indications 50 may be given at a number of different localities.

In carrying out my invention as here embodied, 2 represents an indicating plate preferably formed of porcelain although any 55 suitable material may be used and as illustrated in Figs. 1 and 2 this plate is in the

form of a dial or a circular shape and has a number of indications 3 delineated thereon in radial formation.

Passing through the center of plate or dial 60 is a shaft 4 having a knob 5 fixed thereto for rotating it. To the shaft, for movement over the outer face of the plate is also attached a pointer or hand 6 having its outer end projecting over the edge of the plate at right angles to the body of the hand and then bent upon itself so as to extend beyond the face of the plate for use as finger piece 7 to move said hand and rotate the shaft.

65 This pointer or hand has a slot or aperture 8 through it in order that the indication desired to be made will be visible therethrough. To hold the pointer or hand in the region of each indication said hand carries a light spring 9 for coaction with the notches 10 in the edge of the plate or dial, each of said notches being associated with an indication.

70 On the inner end of the shaft 4 is mounted a wheel 11, preferably a sprocket wheel as shown, on which runs a suitable motion transmitting means 12. This motion transmitting means is preferably made up of two pieces or sections of chain 13 and 14 with intervening sections of wire 15 and 16 connecting them and if found desirable suitable tensioning devices 17, such as turn-buckles, may be interposed in the sections of wire in order to make them taut.

75 In the simplest form of the invention as illustrated in Figs. 5 and 6 the motion transmitting means also runs over another wheel 18, preferably a sprocket wheel of the same size as wheel 11, fixed to the shaft of another indicating unit including a dial or plate and pointer or hand and their component parts identical in all respects to the other unit above described.

80 Considering the indicating plates at the bottom of the drawing in Figs. 5 and 6 to 100 be located on the outside or near the door of a building and the indicating plate at the top of the drawing as on the inside of the building, either in a room, hallway or other suitable location, then when the hand or pointer of the outside indicating plate is turned to indicate who the caller is, such as an iceman, or as soon as the occupants are notified by the door bell or a knock they may ascertain who is at the door by glancing at the inside indicating plate. If, for 105 instance, no ice is desired the hand or

pointer on the inside indicating plate may then be turned to some sentence such as "none to-day" thus quickly indicating the wishes of the occupants without any one of them having to go to the door from some distant point within the building.

Where the device is to be used in a more comprehensive form such as shown in Fig. 7 the motion transmitting means 12 in addition to running over the wheel 11 on the shaft of the outside dial or indicating plate also runs over a wheel 19, preferably a sprocket wheel of the same size as the wheel 11, fixed to a counter shaft 20 carrying a number of other similar wheels 21, 22 and 23 and over these run motion transmitting means 24, 25 and 26, respectively and also over wheels 27, 28 and 29 fixed to dial indicating plate shafts 30, 31 and 32, said last named shafts being associated with the elements of other indicating units located in different and possibly widely separated parts of the building so that when the outside indicating unit is actuated all the other units will be simultaneously actuated so that an occupant hearing the signal that a caller is at the door may proceed to the nearest inside indicating unit and ascertain who such caller is and at the same time indicate his or her wishes to such caller and if there is more than one occupant in the building said other occupants may ascertain who the caller is and the directions given.

Where, in either of these arrangements, a motion transmitting means such as described herein is used it is desirable to limit the movements of the hand or pointer so that it can be carried to a certain point in one direction after which it may be moved in the other direction for proper operation and this is accomplished by providing a stop 33 on one or all of the indicating dials or plates thus preventing the sections of chain from being disengaged from their sprocket wheels.

Where a unit is placed against a wall, the framework or a door frame of the building I prefer that a recess 34 being formed therein to receive the sprocket wheel and a shaft supporting element 35 which may be set against the face of the wall or countersunk as shown in Fig. 2 so as to be covered by the indicating dial or plate when the latter is placed in position and when so arranged holes 36 communicate with the recess 34 for the passage of the motion transmitting means to the wheel on the counter shaft or the one on the shaft of the other indicating plate as the case may be.

In Figs. 3 and 4, I have shown a slight modification of my invention wherein one or more of the indicating plates may be of rectangular shape, such plate being represented by the numeral 37 and having the indication marks 38 in a row either vertical or horizontal. This plate has a slot 39 through which passes the shank 40 of the pointer or hand 41, said shank being connected with a rack 42 meshing with a gear wheel 43 fixed to the shaft 44 suitably journaled, as in a boss 45 on the back of the plate and on this shaft is also fixed a wheel 46 preferably a sprocket for coaction with the motion transmitting means 12 hereinbefore described.

In this form of the invention the hand or pointer 41 may be moved to the desired position which will then actuate the rack 42 slidably mounted in the brackets 47 so as to rotate the gear 43 and thus transmit a rotary motion to the shaft 44 and the wheel 46 and cause the other indicating units to operate whether they be of the form shown in Figs. 1 and 2 or those described and illustrated in Figs. 3 and 4.

Of course I do not wish to be limited to the exact details of construction as herein shown as these may be varied within the limits of the appended claim without departing from the spirit of my invention.

Having thus fully described my invention, what I claim as new and useful is:—

A household indicator comprising in combination, a plurality of indicator dials having indication marks thereon and provided with notches in the edge associated with said indication marks, a shaft passing through each dial, a hand or pointer fixed thereto and having an aperture whereby the indication marks may be viewed therethrough, the outer end of said pointer being bent at right angles to project over the edge of the dial and an end being then bent upon itself to form a finger piece projecting beyond the front face of the hand or pointer, a spring carried by that portion of the hand projecting over the edge of the dial and adapted to coact with the different notches on the edge of said dial, means to limit the movements of said hand, a knob fixed to the outer end of the shaft, a wheel fixed to the inner end of said shaft, and means transmitting motion from one of such wheels from one indicating unit to another of such wheels on another indicating unit.

In testimony whereof, I have hereunto affixed my signature.

MIKE SLAWIENSKI.
